DRAPERY FIXTURE

Jacob A. Wersching, Chicago, Ill.

Application May 3, 1949, Serial No. 81,177

5 Claims. (Cl. 160—348)

1

This invention relates to supports and fixtures for supporting curtains, draperies and the like adjacent to a window, and particularly to a special drapery fixture.

The main object of my invention is to provide simple means for supporting, shaping and holding a flat piece of drapery hemmed at least at the top in a pleated, fixed position in deep, ample and uniform folds extending from the top to the bottom, regardless of length.

Another object is to provide a fixture of the character indicated which is one of a pair and effective to automatically return the drapery to its original pleated and orderly condition when bumped or pushed, or blown by a breeze from an open window, without the necessity of manually rearranging the drapery.

A further object is to have such a fixture which eliminates the use of heavy materials or linings, sewing on of hooks, eyelets, pins, or lead weights, or the sewing in of prearranged pleats or folds.

It is also an object to have a fixture of this type which facilitates using either light or heavy washable material for the drapery than can readily be mangled or ironed flat.

An additional object is to provide a fixture as outlined which has an adjustment for covering more or less wall or window area at will by means of the drapery supported on the fixture.

Other objects and advantages of the invention will appear in further detail as the specification proceeds.

In order to facilitate ready comprehension of this invention for a proper appreciation of the salient features thereof, the invention is illustrated on the accompanying drawing forming part hereof, and in which:

Figure 1 is a plan view of a drapery fixture made according to the invention and embodying the same in a practical form;

Figure 2 is a front elevation of the same drapery fixture as seen from below in Figure 1;

Figure 3 is an end elevation of the same drapery fixture as seen from the left in Figure 2;

Figure 4 is an enlarged section taken on line 4—4 in Figure 1;

Figure 5 is an enlarged section taken on line 5—5 in Figure 1.

Throughout the views the same reference numerals indicate the same or like parts.

The use of draperies and curtains at windows is well nigh universal, and the same holds true for curtain rods and various means resorted to for supporting such curtains or draperies, in posi-

2

tion. Generally speaking, the curtain rods or other means used are usually straight, and the matter of providing folds or pleats upon the drapery involved is ordinarily attended to by the lady of the house who manually adjusts the drapery into the pleated condition desired. When draperies are thus manually arranged, it is usually necessary to use heavy materials and to iron the same or sew or otherwise arrange them to facilitate their holding shape, but despite such expedients, when the draperies are pushed or bumped or possibly blown by a breeze from the open window, they become disarranged and lose the proper pleating or folding which must then be restored manually by careful arrangement so that the condition of the drapery is thus not permanent, but in form constantly deteriorating. This condition thus presents a problem for which no general solution exists, and the problem still remains.

Upon considering this problem, it has occurred to me that a special drapery fixture should be available which is of such nature and construction as to hold the drapery in proper folds from the outset and also capable of restoring the drapery to the folded or pleated condition when it has been disarranged by contact of people therewith or by being blown about by the wind when the window is open. As a result of such consideration, I have succeeded in producing a drapery fixture adapted to be secured to a window frame or trim, as will now be more fully described.

Hence, in the practice of my invention, and referring again to the drawing, upon the upper portion of a window frame or trim 6 is fixed a bracket 7 by means of screws 8 (one shown), the upper end of which is bent outwardly substantially at right angles with the main portion of the bracket to form an upper supporting ledge or lug 9, while spaced a short distance below the lug 9 is a second substantially parallel lug 10 punched through from the bracket itself and leaving an open area 11 in the bracket as a result. Extending vertically through both the lugs 9 and 10 is a rivet 12 which is headed above and below the lugs so as to form a permanent part of bracket 7. Upon the mentioned rivet 12 are mounted a pair of correspondingly-opposite arcuate clamping ends 13, 14 of a pair of metal strips 15, 16 held together by a pair of screws 17 and 18 and virtually forming a swingable arm assembly upon the rivet 12 extending from between lugs 9 and 10. Upon the other end the two strips 15 and 16 terminate in a

further pair of correspondingly opposite arcuate clamping members 19 and 20 clamped about a second rivet 21 extending vertically through the upper and lower arms or lugs 22 and 23 of a supporting yoke generally indicated at 24 and having the intermediate connecting member 25 interconnecting the lugs or arms 22 and 23, above and below which the rivet 21 is headed, as indicated at 26 and 27, so that this rivet resembles the previously-described rivet 12. Intermediate the ends thereof the two strips 15 and 16 have inwardly-pressed portions 15' and 16' mutually engaging against each other to form spacers serving to space the two supporting strips 15 and 16 the proper distance apart so that the clamping effect of screws 17 and 18 can be nicely regulated with reference to their frictional grip upon rivets 12 and 21. Yoke member 24 is so arranged that the intermediate plate portion 25 thereof normally faces forward. A long and substantially horizontal and longitudinally-slotted and adjustable supporting bar 28 is held against the front of plate 25 on yoke 24 by means of a pair of screws 29 and 30 which first hold an anchoring plate 31 against the mentioned bar 28 and extend through a longitudinal slot 32 in the bar and are screwed into yoke plate 25. Due to the presence of two screws 29 and 30, as mentioned, bar 28 is positively held in a horizontal position inasmuch as both screws extend through the mentioned slot 32 and prevent any considerable shift from the horizontal on the part of bar 28, but when screws 29 and 30 are slightly released, they nonetheless allow slideable adjustment of bar 28 between anchoring plate 31 and yoke plate 25, and when the desired position along the bar has been attained, tightening of the screws will again set the bar firmly in position upon yoke 24.

Upon one end of bar 28 is a forwardly-bent end lug 33 disposed substantially at right angles to the main longitudinal portion of the bar and having an inturned and upwardly-bent, U-shaped yoke or cradle 34 with a rivet 35 disposed transversely through lug 33 and the corresponding opposite limb of the U-shaped portion 34 in such fashion as to bridge the gap or space between the two. At the other end bar 28 is rearwardly bent in arcuate fashion at 36 with the rear end bent outwardly again at 37 in substantial parallelism to the main longitudinal portion of the bar and upon the end of offset rear portion 37 is a forwardly-extending lug 38 substantially at right angles to member 37 and also provided as in the case of lug 33 with an inturned U-shaped yoke or cradle 39 with a further rivet 40 extending through lug 38 and corresponding arm 39 of the U-shaped cradle so as to bridge the gap or space between the two. At each end the bar 28 is preferably tapered upwardly or decreased in vertical dimensions, as especially indicated at 41 in Figure 3, to lighten the construction, while the forward ends of lugs 33 and 38 have the upper edges thereof cut away, as indicated at 42 and 43 in Figures 3 and 5, to lighten the structure. The end of bar 28 terminating in lug 33 is intended to be directed toward the intermediate part of the window trim 6, while the other end provided with rear portion 37 and end lug 38 being directed outwardly beyond the end of the window frame or trim 6. At the other end of the window frame a similar fixture as thus far described is intended to be mounted with the corresponding bar 28 directed in opposite direction so that the rearward portion 37 extends beyond the other end of the window trim or frame 6,

while the end carrying lug 33 is directed toward the corresponding lug 33 of the device as shown in Figure 1.

The mentioned yokes or cradles formed by lugs 33 and 38 with their inturned yoke or cradle portions 34 and 39, respectively, are adapted to receive the ends 44 and 45 of a sinuously-formed supporting bar generally indicated at 46, the ends 44 and 45 terminating in upwardly-open hooks 47 and 48 engaging rearwardly of rivets 35 and 40, respectively, with the mentioned ends 44 and 45 resting upon the lower portions or bottoms of the U-shaped cradles 34 and 39 already mentioned. In each case the end 44 or end 45 has the hook 47 or 48 thereof extending substantially up to the level of the upper edge of the sinuous bar 46 with the hook present on the end 44 having a notch 49 with the hook simply formed by the presence of the notch which serves as a seat for the rivet 35 or 40, as the case may be.

The sinuous supporting bar 46 is provided with a series of convolutions 50, 50, etc., arranged in a row and substantially on the same level with the ends 44 and 45, while the end 45 is relatively longer and extends therefore a greater distance rearwardly than the end 44 of the bar, the latter being preferably formed as shown and described from a strip of steel which is sufficiently rigid to hold its form once the desired shape has been applied thereto. Each hook 47 and 48 is externally formed with an arcuate outer edge 51 struck on a radius of the center of rivet 35 when seated in notch 49, so that upon lifting the outer ends of the convolutions 50, 50, the ends 44 and 45 of bar 46 will rotate substantially a quarter turn about the rivets 35 and 40 until the mentioned convolutions are substantially upright when the hooks will be freed from the mentioned rivets and the bar released from yokes or cradles 34 and 39. Restoring the bar into position is just a reversal of the procedure last described.

When a piece of drapery is to be applied to the fixture as thus far described, a flat piece of material suffices for this purpose and is simply hemmed along the upper edge and preferably hemmed also along the lower edge, the upper hem being passed in upon bar 46 and run in and out along the convolutions until the entire bar is occupied. The immediate result is that the drapery generally indicated in broken lines at 52 in Figure 3 hangs down from supporting bar 46 in permanently present convolutions or folds which tend to remain even if the drapery is temporarily disturbed by contact of people therewith or by a breeze from the window.

Preferably, a similarly-shaped ballast bar resembling bar 46 in its convolutions 50 is threaded into the lower hem of the drapery so that the folds or pleats appearing in the drapery will be uniform from top to bottom irrespective of the length of the drapery involved. The lower ballast bar resembling bar 46 may be formed with hooks 47 and 48, if so desired, but the presence thereof is virtually immaterial inasmuch as the lower bar will remain entirely suspended by the drapery and concealed in the hem thereof at the bottom. Similar remarks apply in connection with the application of drapery to a correspondingly-opposite fixture at the other end of window frame 6 as just mentioned respecting supporting bar 46 and the corresponding lower ballast bar similar thereto, the only precaution being that the longer end similar to 45 is disposed at the opposite end of the window frame, that is, outwardly thereof, and the shorter end 44 disposed toward the in-

termidate portion of the window frame, as in the case of the end 44 in the fixture actually shown.

From the foregoing it is evident that due to the presence of bracket 7 and supporting yoke 24 with the intermediate clamping strips 15 and 16 and the rearward extension 37 of slotted supporting bar 28, the mentioned bar with the sinuous supporting bar 46 mounted thereon may be extended forwardly and swung further to the side of the window or brought inwardly toward the intermediate portion thereof, as desired, bars or strips 15 and 16 swiveling on the rivets 12 and 21 to allow such movements, with the result that the drapery on sinuous bar 46 may be swung in upon or away from portions of the window and vice versa with respect to the wall beside the window, and the same will be true of the respectively opposite fixture at the other end of the window frame 6.

Preferably the entire fixture is made of sheet and strip steel, but may be made of other metals, and even of plastic, if so desired, so long as a sufficiently rigid structure results.

Manifestly, variations may be resorted to and parts and features may be modified or used without others within the scope of the appended claims.

Having now fully described my invention, I claim:

1. A drapery fixture including an elongated supporting bar, a bracket adapted to be secured to a window frame or trim, arm means pivotally mounted upon the bracket to pivot on a vertical axis, a supporting member pivotally mounted about a vertical axis on the outer free end of the arm means and having an integral plate thereon, means for adjustably holding the supporting bar in substantially horizontal position on said integral plate, a pair of forwardly-directed lugs upon the ends of said bar disposed at an angle thereto, a sinuous bar terminating at the ends thereof in a pair of rearwardly-directed extremities and adapted to be threaded through a hem upon the upper end of a piece of drapery, and means for detachably mounting the extremities of the sinuous bar individually upon said lugs and supporting said sinuous bar in substantially horizontal position upon said elongated supporting bar.

2. A drapery fixture including an elongated supporting bar, a bracket adapted to be secured to a window frame or trim, an upright pivot member on the bracket, arm means extending horizontally from the latter and having a pair of clamping members at one end frictionally clasping the pivot member, a supporting yoke having a second upright pivot member and an integral front plate, a second pair of clamping members on the other end of said arm means frictionally clasping said second pivot member and carrying said supporting yoke, an anchoring plate holding said supporting bar in horizontal position against said front plate, there being a longitudinal slot in said bar, securing means extending through the anchoring plate and the longitudinal slot in said supporting bar and into said front plate, a pair of forwardly-directed lugs upon the ends of said bar disposed at an angle thereto, a sinuous bar terminating at the ends thereof in a pair of rearwardly-directed extremities and adapted to be threaded through a hem upon the upper end of a piece of drapery, and means for detachably mounting the extremities of the sinuous bar individually upon said lugs and supporting said

sinuous bar in substantially horizontal position upon said elongated supporting bar.

3. A drapery fixture including an elongated supporting bar, means for supporting the bar in horizontal position adjacent to a window frame, a pair of forwardly-directed lugs upon the ends of said bar disposed at an angle thereto, a pair of opposite inturned U-shaped yoke members formed on said lugs and constituting supporting cradles, a pair of horizontal pins transversely disposed through said lugs and the corresponding opposite portions of the yokes or cradles in such fashion as to bridge the spaces therebetween, a sinuous bar terminating in a pair of rearwardly-directed extremities, and upwardly-open hooks upon the rear ends of said extremities adapted to engage beneath said horizontal pins when said extremities are seated in said supporting cradles.

4. A drapery fixture including an elongated supporting bar, means for supporting the bar in horizontal position adjacent to a window frame, a forwardly-directed lug upon one end of said bar disposed at a right angle thereto, the other end of said bar being rearwardly offset, a second forwardly-directed lug upon the rearwardly-offset end of said bar also disposed at substantially right angles to the offset end, a pair of opposite inturned U-shaped yoke members formed on said lugs and constituting supporting cradles, a pair of horizontal pins transversely disposed through said lugs in the corresponding opposite portions of the yokes or cradles in such fashion as to bridge the spaces therebetween, a sinuous bar terminating in a pair of rearwardly-directed extremities with one extremity longer than the other, and upwardly-open hooks upon the rear ends of said extremities adapted to engage beneath said horizontal pins when said extremities are seated in said supporting cradles, the upwardly-open hook upon the longer extremity being seated in the yoke or cradle associated with the lug upon the rearwardly-offset end of the supporting bar.

5. A drapery fixture including an elongated supporting bar, a bracket adapted to be secured to a window frame or trim, an upright pivot member on the bracket, arm means extending horizontally from the latter and having a pair of clamping members at one end frictionally clasping the pivot member, a supporting yoke having a second upright pivot member and an integral front plate, a second pair of clamping members on the other end of said arm means frictionally clasping said second pivot member and carrying said supporting yoke, an anchoring plate holding said supporting bar in horizontal position against said front plate, said supporting bar having an intermediate longitudinal slot therein, securing means extending through the anchoring plate and the longitudinal slot in said supporting bar and into said front plate, a forwardly-directed lug upon one end of said supporting bar disposed substantially at a right angle thereto, the other end of said supporting bar being rearwardly offset toward the window frame, a second forwardly-directed lug upon the rearwardly-offset end of said supporting bar also disposed substantially at a right angle to the offset end, a pair of opposite inturned U-shaped yoke members formed on said lugs and constituting supporting cradles, a pair of horizontal pins transversely disposed through said lugs in the corresponding opposite portions of the yokes or cradles in such fashion as to bridge the spaces therebetween, a sinuous bar terminating in a pair of rearwardly-directed extremities with one extremity longer than the other, and up-

wardly-open hooks upon the rear ends of said extremities adapted to engage beneath said horizontal pins when said extremities are seated in said supporting cradles, the upwardly-open hook upon the longer extremity being seated in the yoke or cradle associated with the lug upon the rearwardly-offset end of the supporting bar.
